O. KUPFERMAN.
SOCKET FOR INCANDESCENT LAMPS.
APPLICATION FILED APR. 6, 1917.

1,301,456.

Patented Apr. 22, 1919.

Inventor
Oscar Kupferman
By his Attorney
Mark Drucker

UNITED STATES PATENT OFFICE.

OSCAR KUPFERMAN, OF BROOKLYN, NEW YORK.

SOCKET FOR INCANDESCENT LAMPS.

1,301,456.

Specification of Letters Patent. Patented Apr. 22, 1919.

Application filed April 6, 1917. Serial No. 160,303.

To all whom it may concern:

Be it known that I, OSCAR KUPFERMAN, a citizen of the United States, and a resident of Brooklyn, in the county of Kings 5 and State of New York, have invented certain new and useful Improvements in Sockets for Incandescent Lamps, of which the following is a specification.

The present invention refers to improvements in sockets for incandescent lamps and has for this object to simplify the construction of a key-actuated socket, adapted to operate for making and breaking the current, so that all coöperating parts can be 15 readily and quickly assembled and are easily accessible for repair.

There is a general drawback attached to the hitherto-known sockets which resides in the attachment of the hood or cover of the 20 shell containing the insulating base and "make" and "break" switch. In all hitherto used sockets, the two parts, namely, the shell or casing and the cover can be disconnected only with great difficulty, requiring 25 a strong pressure on the shell or a downward pull, which frequently causes damage to the device itself and also to the chandelier. Others, on the other hand, have a construction which at a slight jerk, will cause the 30 disconnection of the two parts. This invention has, therefore, another object, namely, to obviate the above named drawbacks and to provide a construction, whereby the connection and disconnection of the shell and 35 cover or hood can be effected in the simplest and quickest way, and whereby an accidental disengagement of the parts will be rendered impossible.

With these and other objects in view, my 40 invention consists in the construction, combination and arrangement of parts as will be hereinafter fully described and set forth in the appended claim.

In the drawing, which forms part of this 45 specification and in which similar reference characters denote corresponding parts, Figure 1 is an elevation of my new socket, with some parts broken away to show details of construction; and Fig. 2 is a vertical section 50 of the shell, showing the switch in a front elevation.

Referring specifically to the drawing, 20 denotes the hood which is adapted to fit over the top opening of the shell or casing 21 containing the insulating base 1. In order 55 to secure the hood 20 to the shell 21, but

at the same time allow the easy removal thereof for purposes of repair, inspection or the like, I provide the following construction:

The shell 21 at its upper end is provided with a number of angular incisions or slots 21' substantially of the form shown. The cover or hood 20 which is of the usual shape is provided with a hollow sleeve-shaped 65 projection 20' which extends from the top of the cover into the latter. This sleeve 20' serves as a bearing for a spiral spring 22, which is mounted around said sleeve 20' and has one of its ends fixed to the top of 70 the cover 20. The spring is of such a length that when the cover 20 is applied to the shell 21, its lower or free end will tend to project into the casing or shell 21. Projecting from the inner circumference of the cover 75 20, are pins 23 or other suitable members, which in number correspond with the number of slots 21' and which are adapted when the cover is applied to engage the said slots and upon turning the cover slightly around 80 its vertical axis to enter the vertical parts 21² thereof and to thereby retain the cover in position. The spring 22 by reason of its expansion tendency will insure engagement of the pins 23 with the parts 21² of the slots 85 21' and prevent accidental disengagement or disconnection of the cover and shell. Loosely placed against the free end of the spring 22 is a disk 24 of suitable insulating 90 material and of a diameter substantially equal to the inner diameter of the cylindrical bottom part 20² of the cover 20. This disk normally, i. e. when the cover is removed from the shell will rest on the pins 23, a pressure being exerted thereon by the spring 95 22. But when the cover 20 is applied to the shell 21, the disk 24 will be engaged by the upper edge of the shell 21 and will be raised against the tension of the spring 22, thereby compressing the latter. The reaction of the spring will be a force on the pins 23 insuring their engagement in parts 100 21² of the slots 21'.

The insulating base 1 when positioned in the casing or shell 21 will have its upper 105 face about even with the upper edge of the shell. In consequence thereof, it will be clear, the screwing in of the incandescent lamp into the screw shell 11 of the insulating base, will have the effect to still more 110 tighten the cover to the shell because of the reaction of the compressed spring 22. In

order to remove the cover, it will be necessary to first press the shell upwardly against the tension of the spring and then give it or the cover a short turn so as to cause the 5 pins to enter the open part of the slots through which they can escape.

It is understood that various modifications may be made in the construction of the device without departing from the principle 10 of my invention and I therefore do not wish to restrict myself to the details shown and described.

What I claim and desire to secure by Letters Patent, is:

15 In a lamp socket, a shell having angular recesses at its upper end, a cover to fit around the upper end of said shell and having projections adapted to engage the said recesses and form therewith a bayonet joint, 20 a spiral spring in said cover of which one

end is fixed to the latter and the free end of which has the tendency to project into the shell, a comparatively thin disk of insulating material loosely mounted in said cover and adapted normally to rest on the 25 said projections of the latter and to be acted upon by said spring, but upon assembling the said shell and cover to be engaged by the said shell and moved against the tendency of the said spring whereby the said shell and 30 cover when connected by the bayonet joint become firmly locked with each other.

Signed at New York, in the county of New York and State of New York this 5th day of April A. D. 1917.

OSCAR KUPFERMAN.
